UNITED STATES PATENT OFFICE

GEORGE VIRNEBURG, OF NEW YORK, N. Y.

WASHING IMPLEMENT

Application filed March 6, 1930. Serial No. 433,528.

This invention relates to a wash sponge or like washing implement and has for its main object to provide an implement that can be easily and conveniently slipped over the user's hand and be retained in position while in use.

Another object is to provide such implement with means for holding a piece of soap, so that when said implement is being rubbed 10 against the user's body foam will be formed on the outside thereof.

A still further object of this invention is to construct the implement of an elastic material in form of a tubular body so that owing 15 to its elasticity it can be applied to hands of different sizes and will be retained thereon by friction, thereby eliminating any special fastening means.

Still another object of this invention is to 20 construct the means for holding the soap, in form of a pocket on the inner face of the implement and to make said pocket of a non-porous material, so that the soap when contained in said pocket will not form foam on 25 the hand.

And a still further object is to so shape the tubular body that the latter can be easily and conveniently turned inside out to permit the insertion of a fresh piece of soap, and that 30 while applied to the hand it will permit free movement of the fingers and wrist of the hand.

With these and other objects in view my invention consists substantially in the novel 35 combination, arrangement and construction of parts as will be hereinafter more fully described and defined in the appended claims.

In the accompanying drawings which form part of this specification and in which 40 similar references denote corresponding parts:

Fig. 1 is a perspective view of one embodiment of my device;

Fig. 2 is a cross sectional elevation along 45 line 2-2 of Fig. 1;

Fig. 3 is a side elevation partially in section of my device; and

Fig. 4 is a perspective view of one method of making my implement.

Referring to the drawings Figs. 1-3 in-

clusive, my device may be constructed of a piece of expandible material 10 such as rubber sponge or the like which is adapted to be formed into a tube by connecting opposite edges 11 and 12 either by gluing vulcanizing or otherwise suitably fastening the same. The portion of the tube where the joint is made is shorter than the opposite portion 13 of the said tubular body and the ends of said body taper from said joint to said opposite face. The body 10 is made porous by providing it with a plurality of slits or openings 14 for a purpose hereinafter specified.

The interior face of said body if made of rubber sponge may be covered over its entirety with a non-porous thin rubber sheet 15 through which extend the slits 14. Internally of said tubular body and mounted on said sheet 15 over said openings 14 is mounted a sheet of flexible non-porous material 16 of sheet rubber, rubberized cloth or the like which may be fastened by gluing of its edges to the inner face of said sheet 15 or in any other way. A portion of the edge of said sheet is left unglued as at 16' so that a cake of soap S or the like may be inserted into the pocket formed by said sheet 16.

In order to provide a suitable rubbing and massaging surface which will be free from soap, I provide the member 17 which may be 80 of similar material to that of said tubular body or of any other suitable material and of any desired shape or size. The said member may be suitably fastened to said tubular body as for instance by gluing it or in any other way, over the joint between the edges 11 and 12 of said member 10, said member serving thereby incidentally also as an additional joint between said edges.

In use my device is operated as follows:— 85

The tubular body may be turned inside out, soap inserted into the pocket formed by said sheet 16 and turned back to normal. Then the hand is inserted into the tubular body with the palm over said pocket. The said body being of expandible material stretches to accommodate itself to differently sized hands and is frictionally retained thereon. If now said body is wetted and rubbed over anything such as the body or other sur-

faces, foam from soap suds forms and is extruded through the openings 14 onto the outer face of said tube and the body or other surface may be washed with said foam and is 5 rubbed and massaged at the same time. If further massage without foam is desired the surface of the body being cleansed may be rinsed and the member 17 which is free from such foam may be used. Since the pocket 10 forming member 16 is non-porous practically none of the foam will form on the hand of the user as the latter is in no direct contact with the soap.

The fact that the edges of the tubular body 15 are tapered affords freer movement of the hand and fingers in said body and adds to the flexibility of the device. After use the device may be rinsed and used over again.

To facilitate the manufacturing of the device 20 in large quantities and reduce the cost thereof and eliminate waste of material the following method may be used.

A long tube 18 may be initially cast or formed and subsequently cut up into individual 25 sections as shown by the dotted lines 19 (Fig. 4). The individual sections may then be perforated or slotted and provided with pockets as the device shown in Figs. 1-3 inclusive.

30 My device may be modified in many ways and I do not wish to be limited to the details shown and described.

What I claim is:—

35 1. A washing implement comprising a tubular body of sponge rubber, an inner lining of non-porous rubber covering the entire inner wall of said tubular body, and a non-porous sheet of rubber mounted on said lining to form a soap pocket between itself and said 40 lining, said lining having perforations beneath said non-porous pocket forming sheet which also extend through said porous body, whereby soap foam may pass from said pocket to the exterior of said tubular body.

45 2. A washing implement comprising a tubular body of porous material, an inner lining of non-porous material covering the inner wall of said body, and a non-porous sheet mounted on said lining to form a soap pocket 50 between itself and said lining, said lining having perforations beneath said non-porous pocket forming sheet whereby soap foam may pass from said pocket to the exterior of said tubular body.

55 3. A washing implement comprising a tubular body of porous material, an inner lining of non-porous rubber covering the inner wall of said body and a non-porous rubber sheet mounted on said lining to form a soap pocket 60 between itself and said lining, said lining having perforations beneath said non-porous pocket forming sheet whereby soap foam may pass from said pocket to the exterior of said tubular body.

65 4. A washing implement comprising a tu-

bular body of porous material whose ends are cut on a bias along planes which intersect, an inner lining of non-porous material for said body, and a non porous sheet mounted on said lining to form a soap pocket between itself and said lining, said lining having perforations beneath said non-porous pocket forming sheet which also extend through said porous body whereby soap foam may pass from said pocket to the exterior of said tubular body.

5. A washing implement comprising a tubular body of sponge rubber whose ends are cut on a bias along planes which intersect, an inner lining of non-porous rubber covering the entire inner wall of said body, and a non-porous rubber sheet mounted on said lining to form a soap pocket between itself and said lining, said lining having slits beneath said non-porous pocket forming sheet which also extend through said porous body whereby soap foam may pass from said pocket to the exterior of said tubular body.

In testimony whereof I affix my signature.
GEORGE VIRNEBURG.
